UNITED STATES PATENT OFFICE

LAURENCE LEIGH MEAD, OF CARLINVILLE, ILLINOIS

INTERNAL-COMBUSTION ENGINE

Application filed June 14, 1926. Serial No. 115,898.

This invention relates to internal combustion engines generally known to the art as rotary sleeve valve and more particularly to the rotary sleeve valve wherein the sleeve 5 either constitutes the cylinder itself or encompasses it and is actuated by a force transmitted from the crank-shaft and applied to the inner end and to one side of the sleeve valve. The rotating sleeve engine of this type has failed to achieve the success attained by the reciprocating type, presumably on account of a "lack of efficiency and completeness in detail, which are after all the essential elements which mark the line between success 10 and failure in invention." The words are quoted from the Scientific American of May 13, 1911 on "The Valveless Engine" by H. H. Gordon of the United States Patent Office. The object of this invention is to supply such 15 completeness in detail and add to the efficiency of this type of engine. The same article states that "the rotating valve as a rule has a larger frictional loss than a reciprocating valve. To offset this however, we have 20 the ability to give the valve better turning, and a complete absence of inertia effects." It stands to reason that two valve sleeves of the same size and otherwise identical should have 25 the same frictional loss, even though one is moved longitudinally and the other about the axis. If the rotary moving valve has the greater frictional loss, the loss must lie in the application of the driving force, rather than 30 in the difference of direction of the two movements. This invention has much to do with 35 this fact. In a reciprocating sleeve the driving force is applied to one side, and successful sleeves of this type are very long, and the shorter they are, the greater the frictional 40 loss. If their length were reduced to a mere ring, the friction would be so great that they would be practically immovable. But this invention has to do with rotary sleeves. The 45 rotary is generally driven by a ring gear attached to one end of the sleeve and actuated by a spur connected by gearing to the crank-shaft, in which case the valve itself serves as a rather clumsy shaft or axle for the gear, and its casing as the bearing for the shaft. 50 This ring gear is a gear wheel, but it differs

from most gears in having no central hub. The place where its hub and axle should be is occupied by the pitman, therefore it may be said that this engine has a serious defect. To attempt to turn any gear wheel or other 55 wheel without a suitable axle or spindle is to occasion great frictional loss. Imagine a vehicle wheel with a hub nearly as large as the rim of the wheel and we may easily understand why the frictional loss of the rotating 60 sleeve is greater than the reciprocating. To have great frictional loss is also to cause excessive wear, and as the driving force is applied to one side only, the wear is also on one side only. A wear on one side would tend to 65 throw the valve sleeve off its true axis as will be shown in the attached drawings, and would result in faulty contact of the sleeves at the port openings with leaky compression and loss of power. In the case of an engine where 70 the valve gears are enmeshed in a train and driven from a single gear, the aforesaid wear and friction would be increased in proportion to the number of valves in the train; the first driven sleeve having the greatest friction and 75 the last sleeve the least. From the foregoing it would appear that the rotary sleeve valve engine is short lived and impractical, unless some means should be devised to overcome 80 this excessive frictional loss. The chief object of this invention is to provide the valves with a means for carrying the load due to thrust of the driving mechanism and thereby prevent rubbing of the valve on adjacent parts resultant from said load. The said 85 means being a spindle or axle operatively connected with the valve and so disposed as to carry said thrust in the proper manner. In the case of the ring gear arrangement hereinbefore referred to wherein the thrust has 90 a tendency to shove the valve from its axis, it appears necessary, in order to accomplish the desired result, that the ring gear be rolled against another rolling element; a rolling contact being considered far better than a 95 sliding and grinding contact at this point. The rolling elements are operatively connected with the aforesaid spindle or spindles in such a manner that the entire thrust of the actuating mechanism is carried on the spin- 100

dles, and there is no grinding of the ring gear or the valve on the frame at this point. As a modification of this idea, I propose to dispense with the spindle, and roll the ring gear against suitable rollers which roll around in an annular track or race. These rollers may be cylindrical, conical or spherical as best suits the individual requirements. It may be well to mention here that the types of rollers used depends on whether the gear thrusts are radial only, or are both end and radial. I am aware that spherical rollers have been used in connection with sleeve valves, but I know of no case in which these spherical rollers have been designed to take the place of a missing axle. On the contrary they are usually placed so as to carry the weight of the valve in the vertical types which is insignificant in the smaller engines, and occasionally to carry end thrust due to cylinder pressure.

In the carrying out of my invention I have incorporated certain construction details which have little to do with this invention except to improve its appearance and practicability and I do not limit myself to these details.

The rotary valve sleeve with multiports is old in the art and it is not my intention to devote much space to a description of its construction and operation. There is no question it has points of superiority over the reciprocating valve sleeve, having no lost motion and being absolutely vibrationless as far as the valves are concerned, thereby adding somewhat to the power output and the quiet running of the motor. It has peculiar adaptability to the conditions met with in designing valves for the Otto cycle engine. The difficulty encountered in designing link motions for reciprocating valves is well known. Therefore we may assume that a rotary sleeve valve engine which is perfectly balanced and as long lived as the reciprocating valve engine and readily taken apart and assembled should be much superior to any reciprocating sleeve engine. I attain the aforesaid objects by the mechanism illustrated, in the accompanying drawings in which:-

Figure 1 is a vertical cross section through cylinder and crankcase showing the antifriction rollers bearing against the driven end of the sleeve. Fig. 2 is a half diagrammatical sectional view of the valve sleeve in its casing exaggerated to illustrate the harmful effect caused by the thrust of the driving spur for which said antifriction device is a remedy. Fig. 3 shows a modified form of the antifriction device employing the use of balls or rolls and annular race instead of fixed rolls. This view also shows the valve shaft bearing with the crankcase detached from the cylinder bloc. Fig. 4 is a longitudinal vertical section on the line A—A of Fig. 1 through the

crankcase and two cylinders, with certain parts broken away for convenience. Fig. 5 is a view looking at the underside of the cylinder bloc illustrating the fixed rolls and means for adjusting same, certain bolts shown in section for convenience. Fig. 6 is a detail view of the valve shaft 15 bearing in modified form. Figs. 7 to 11 are cross sectional views through the cylinders and valve sleeves showing the valve in its various positions in the valve cycle. These views show a double sleeve, the inner sleeve fixed, this invention being adaptable to both double and single sleeves. Fig. 12 shows a casing with inlet and exhaust on the same side, it being obvious that the geometrical design of these valves permit of any desired arrangement of casing ports. Fig. 13 shows the application to a multiport casing.

In Fig. 7 the valve is in position at the middle of the suction stroke with exhaust port closed. In Fig. 8 both ports are closed for compression. In Fig. 9 both ports are still closed for firing, yet have moved one sixteenth of a revolution. In Fig. 10 the intake remains closed and the exhaust is wide open in the midst of the expulsion stroke. Fig. 11 shows the exhaust closing and the intake about to open at the top of the expulsion stroke, and the cycle is repeated. The ports are automatically open the widest when the piston has attained the highest velocity and vice versa.

Similar numerals refer to similar parts throughout the several views. Referring especially to Figs. 1 and 4, the numeral 1 represents the crankcase, 2 the crankshaft journaled in bearings 3. The crankcase is usually divided into two parts 4 and 5 on the line 6 and held together by bolts 7 and lugs 8. The cylinder 12 is secured to the upper crankcase portion and is composed preferably of a casing 15 and a sleeve valve 16, telescopically and revolvably mounted therein. This sleeve valve may be held against longitudinal movement in any suitable manner, as by a rim or flange 72 adapted to turn in a seat 73. In this construction it is necessary that the head be detachable and the ring gear 19 be removable, as will be more fully described hereinafter. The piston and pitman are shown at 17 and 18. In the type of sleeve valve shown in the drawings, the valve is usually turned by a ring gear which is held against rotation with respect to the valve in some suitable manner, and it is in turn driven from the crankshaft by some suitable gearing, as by the gear 20. I have shown the gears 20 mounted on a shaft 24 and the shaft turned by a link belt 21 running over toothed pulleys 22 and 23. Often in this type of engine the ring gears 19 are enmeshed and driven by a single driving gear which only multiplies the load on the first driven gears, and the driver should be situated near the middle of

the string to reduce this multiplied load. In Figs. 1, 2, 4, and 7 to 13 the ports in the valve sleeve are indicated at 25, 26, 27, and 28 while in the casing the inlet port is indicated at 29, and the exhaust port at 30.

If it is desired to affix the ring gear 19 to the valve in such a manner as to be easily removable, I propose to provide the lower extended end of the valve with longitudinally disposed slots 31 engaging feathers or keys 32 on the inner face of the gear. The gear is held against longitudinal movement on the sleeve by a shoulder at 35 and a screw ring and lock ring 33 and 34.

In order to provide the gear shaft 24 with suitable bearings, I suggest the form of bearings shown in Figs. 1, 3, 4, 5, and 6. In the type of engine in which the cylinder is detachable from the base, the cylinder base may be provided with a bracket 13 with a rib 14, and a bearing seat 37 is affixed to the bracket 13, and the cap 36 affixed to the crankcase. When the crankcase and cylinder block are assembled the gear shaft 24 is normally held between them as in a pillow block. When the crankcase is removed the shaft 24 is held to seat 37 by a clip or strap 40 so that the timing of the valves is not disturbed. Of course these bearings should be bushed or babbitted as at 38 and 39. What may be a better form of bearing is shown in Fig. 6 in which the cap 41 is of the usual adjustable type, held in place by the cap screws 42.

As mentioned hereinbefore, the rotary sleeve valve as heretofore constructed is without a suitable axle for its driving gear, the valve itself being required to do duty as the axle for the hollow ring gear, and the valve casing as its bearing. Under the most favorable conditions, for instance in the case of the cylindrical type of valve in which there is no load other than the weight of the valve itself, such a construction is in direct violation of the most fundamental principles of applied mechanics. But impose on the gears a heavy load, as for instance the type of valve wherein the ports are sealed by cylinder pressure, and still further multiply this load by enmeshing these gears in a string, and we can imagine what a tremendous strain would be imposed on the driving mechanism. But I propose to provide the valves with an axle which will carry all loads that may be imposed on the gears, and an axle which will at the same time be not in the way of the pitman. To provide the rotary sleeve valve with an axle appears to be an entirely new idea in view of the prior art and I feel justified in claiming this idea in its broadest sense. In the type of sleeve valve shown in the illustrations attached I propose to carry out this idea in the following manner. I provide the ring gear 19 with a concentric rim as for instance the rim 47 which is adapted to roll against another rolling element so that the

hollow gear is guided and held to its normal axis by the said rolling elements. In the attached drawings, Fig. 1, I have shown the rolling element as a roll 44, provided with a spindle 46, and this rolling element should be as large and durable as the nature of the construction will admit. In Fig. 5, I have shown a plan view of these rolls looking at the under side of the cylinder base and have placed the roll 43 so that it will meet the shoving action of the gear 20, and also show another roll 44 with a spindle 46 which serves as a guiding means against any tendency of the hollow gear to be thrust in that direction. It may be possible that these rolls and spindles can be made sufficiently durable as to wear a reasonable time without a take-up, but I have provided a means of adjustment if one should be required. The spindles 45 and 46 are mounted on lever like arms 48 and 49 which swing on the fulcrums 50 and 51 secured to the cylinder base, and their opposite ends provided with a slot and bolt clamping means 54 and 55. This construction permits the rolls to be swung against the roll track or rim 47 to take up any possible wear on them. By placing the rolls at a point adjacent to the fulcrums 50 and 51 the greater amount of strain is placed on the fulcrums and thereby reducing the strain on the clamps 54 and 55 which are held only by friction. As a further precaution against slippage of the clamps, the abutting screw 56 is threaded through the lug 57 and brought to bear against the arms 48 and 49. The number of rolls depends on the nature of the requirements, and any suitable adjustment may be employed. I have shown only two rolls as they appear to be chiefly required on that side upon which the wear occurs and on the opposite side I have shown a section of sliding surface 60 which may suffice to guide the hollow gear, although a roll or two which is non-adjustable might better serve.

Fig. 3 shows a modified form of this rolling contact in the shape of rollers which are interposed between the ring gear 19 and adjacent parts and roll around in a suitable race. These rollers are shown here in the spherical form, commonly called balls, although they may be cylindrical or conical. Referring to the drawing the so called balls 62 roll around in the race in the annular cup 65 which is suitably held in the annular recess 66 in the cylinder base. The cone race is indicated at 64. The form of roll bearing shown here is designed to carry a combined radial and end thrust, which is the species of thrust exerted by the spiral gear shown. The balls 63 oppose the balls 62 and the bearing assumes the form of a hub bearing, and is therefore adjustable, the adjustment being accomplished by means of the screw ring and lockring 33 and 34 which engage threads on the lower end of the valve and slide the

cone 64 along the valve, the valve and cone being provided with the slots 31 and keys 32, to prevent turning on the sleeve. This type of rollers may be objectionable because they are too far from the center and subjected to too much wear for much the same reason that sliding bearings are objectionable, but rolling contact here is greatly preferable to sliding and grinding. And this objection may be overcome to some extent by reducing the speed of valve travel by the use of multiports.

If we should attempt to use the rolling bearings described herein and not make any further changes in the construction we would find that the sleeve valve still performed as the axle for the gear 19 and the casing as the bearing; and the herein described rolling bearings would not function at all. The reason for this is clear. The valve and casing being in snug contact at the point where the ring gear is attached, would not permit any radial movement of the ring wheel, and it would be held away from any contact with the rolling elements. It is necessary that this gear should have some freedom of movement in a radial direction in order to make contact with these rollers, and at the same time not disturb the concentric alignment of the ported end of the valve. This may be accomplished as is shown in the drawings by providing a space indicated by the shade line 61, in Figs. 1 and 4 and by a broken line in Fig. 5 and more clearly in Fig. 3. This permits the valve gear 19 slight freedom of movement radially while the ported end of the valve remains in close sealing contact. In Fig. 5 the space 61 is indicated as only part way around, it being thought that the gear and valve are shoved to that side only in the species of valve shown.

In Figs. 1 and 4, the cylinder head extension 70 is shown with a recess 71, which communicates with the extended end of the ports, one for each port in the casing, thereby increasing the size of the ports and aiding in the quick escape of gases.

The partly diagrammatical view in Fig. 2 is intended to show the ill effects resulting from lateral thrusts and the necessity of using antifriction bearings as just described. The number 15 designates the jacketed casing, 16 the valve sleeve, 25 and 27 the valve ports, and 29 and 30 the casing ports, 20 the driving spur and 19 the driven ring gear. The direction of thrust of the driver is indicated by arrows and the sleeve is shown slightly off its axis, a shoulder is worn in the sleeve at 67; the sleeve is apart from its casing at 69 through which space the compressed gases may escape to the crankcase. This is of course exaggerated but such a condition may exist in a more or less degree.

As shown in Figs. 7 to 13 preferably a four port sleeve is used in this engine which is of the Otto-cycle type, the ports being spaced

equidistantly about the circular cross section of the valve shell. By this arrangement, the circumference of the circles describing the circular cross section of the sleeve is divided into four equal parts or arcs of 90° each and a complete operation of the valves or a valve cycle takes place as each of these arcs passes a given point in the rotation of the sleeve. In other words, during a quarter of a revolution of the valve, the crankshaft makes two revolutions and the piston four strokes. For a complete revolution of the valve, the crank-shaft makes eight revolutions and the piston sixteen strokes. It being known that each separate inlet and exhaust valve opens and closes during approximately one stroke of the piston, it follows that a given point in the valve should travel one-sixteenth of a revolution as each valve port opens and closes, or 22½° of the circle. Each valve opening should have a width of approximately 11½° varying in accordance with the lead given the exhaust and the retarding of the inlet valve. Assuming the piston and the inner circumference of the valve to be four inches in diameter and the stroke five inches, the valve will travel about 12½ inches during a complete revolution while the piston travels 80 inches, or for a four inch stroke 64 inches. In either case the valve travel does not exceed 1/5 the piston travel.

What I claim is:—

1. In an internal combustion engine of the class described the combination of a suitable crankcase, crankshaft, pitman and piston; of a cylinder casing mounted thereon with a sleeve valve telescoped and in sliding revolute contact therewith, with ports adapted to register; of actuating mechanism connected with the crankshaft for suitably actuating said valve, and means for carrying the radial load of said actuating mechanism and preventing rubbing of the valve on adjacent parts resultant from said load; said means being a spindle so disposed as to carry said thrust or load; said spindle being operatively connected with said valve by parts rotatively co-operating with said spindle.

2. In an internal combustion engine of the class described, the combination of a suitable crankcase, crankshaft, pitman and piston; of a cylinder casing mounted on the crankcase with a sleeve valve telescopically disposed within the casing with suitable ports; of actuating mechanism adapted to transmit a suitable turning motion from the crankshaft to the valve; means for carrying the radial thrust of said actuating mechanism and preventing rubbing of the valve against adjacent parts resultant from said thrust; said means being a spindle so disposed as to carry said thrust, said spindle being operatively connected with said valve by parts rotatively co-operating with said spindle.

3. In an internal combustion engine, the crankcase and crankshaft, pitman and piston; a cylinder casing on the crankcase with a ported sleeve valve telescoped and in sliding revoluble contact therewith; the valve being driven by a gear of annular formation; a means for turning said gear by a thrust on the rim and parallel to the tangent of said gear, said thrust tending to shove the gear and valve from its axis; means for meeting said shove by a rolling contact interposed between the rim of the annular gear of the valve and the frame of the engine, and thereby preventing uneven wear of the valve on its casting.

4. In an internal combustion engine, the crankcase and crankshaft, pitman and piston; a cylinder casing on the crankcase with a ported sleeve valve telescoped and in sliding contact therewith; a screw gear on said valve, a rim on said gear, said valve held to its axis by moving and guiding connection with the frame of the engine; a means for turning said gear on the rim by a thrust and parallel to its tangent, said thrust tending to shove the gear from its axis; means for meeting said shove by a rolling contact interposed between the rim of the gear and the frame of the engine, and thereby preventing rubbing of the gear on the frame.

5. An internal combustion engine having a frame and a crankcase, crankshaft, pitman and piston; a ported cylinder casing on the crankcase and a ported sleeve valve telescoped and in concentric, sliding contact therewith at the ports; the valve being actuated by an annular gear operatively connected with the valve, said gear being held to its normal axis by moving and guiding connection with surrounding parts; a rolling contact interposed between the gear and the frame of the engine for preventing friction between said gear and the surrounding parts caused by the thrust of the actuating means, said actuating means being a thrust transmitted from the crankshaft and applied to the periphery of the gear; means for permitting slight radial movement of the gear from its normal axis, independently of the concentric alignment of the valve and the casing at the ports.

6. In an internal combustion engine of the class described, the crankcase, crankshaft, pitman and piston; a cylinder casing on the crankcase and a sleeve valve telescoped therewith with the usual ports; the driven end of the valve being of hubless, annular cross section, and held to its axis by moving connection with adjacent fixed elements; a force transmitted from the crankshaft for actuating said valve by a thrust on one side of the axis thereof; means for carrying said thrust and preventing rubbing of the valve on adjacent fixed elements resultant from said thrust; said means being a fixed revoluble roll with a

suitable spindle so disposed that the driven end of said valve should roll thereagainst and be held to its axis; substantially as, and for the purpose described.

7. In an internal combustion engine of the class described, the crankcase, crankshaft, pitman and piston; a cylinder casing on the crankcase and a sleeve valve telescoped therewith with the usual ports; the end of said valve projecting into said crankcase, and held to its axis by moving connection with adjacent fixed elements; means from the crankshaft for actuating said valve by a thrust on one side of the axis thereof; means for carrying said thrust and preventing rubbing of the valve on adjacent fixed elements resultant from said thrust; said means being a plurality of fixed revoluble rolls with suitable spindles, and so disposed that the driven end of said valve should roll thereagainst and be held to its axis; substantially as and for the purpose described.

8. An internal combustion engine of the class described having crank case and crankshaft, a cylinder casing mounted thereon having a piston with pitman connections with a crankshaft, the fixed parts of the engine comprising the frame thereof; a rotary sleeve valve mechanism telescoped with the cylinder casing and in slidable revoluble contact therewith; said valve having ports to register with the casing ports; mechanical means for preventing rubbing contact and wear of the sleeve against the frame of the engine comprising fixed revoluble rolls adjustable with respect to the valve sleeve, and so placed as to oppose the lateral thrusts on the valve caused by the valve actuating mechanism; said valve actuating mechanism being a force transmitted from the crankshaft and acting on one side of the sleeve for causing suitable rotary movement of the same; all substantially as described herein.

9. An internal combustion engine of the class described, having crank case and crankshaft, a cylinder casing mounted thereon and a sleeve valve mechanism telescoped within the casing with ports to register with the casing ports, the sleeve in slidable revoluble contact with the casing; the fixed parts of the engine comprising the frame thereof; means connected with the crankshaft and acting on one side of said valve sleeve and adjacent to the periphery thereof for causing suitable rotary movement of the sleeve; mechanical means for preventing rubbing contact and wear of the sleeve against said frame of the engine resultant from thrust of the driving mechanism comprising fixed revoluble rolls adapted to bear against said sleeve, the rolls affixed to an arm adapted to swing from one end, the other end clamped against movement and movable and adjustable with respect to the sleeve; the usual piston reciprocating within the valve sleeve and

casing, with pitman connections with the crankshaft; all substantially as described.

10. For the rotary sleeve valve engine herein described, the fixed revoluble rolls 43, attached to the swinging arm 48, the rolls 5 adapted to bear against the sleeve 16, the arm 48 having the slot and clamp 54 at the movable end; said rolls being affixed to the arm adjacent to the pivoted end thereof, substantially as described and for the purpose specified.

11. An internal combustion engine of the class described having a crankcase and crankshaft, a cylinder mounted thereon, the fixed 15 parts of the engine comprising the frame thereof; a combustion chamber within the cylinder and a piston operating therein having pitman connections with the crankshaft; a sleeve valve and casing in working cooperation with the combustion chamber; means for causing suitable rotary movement of the sleeve valve from the crankshaft acting on one side of the valve and adjacent to the periphery thereof; means for preventing rubbing contact and wear of the valve on one 20 side of said frame caused by the resultant thrust of the valve driving mechanism, said means being rolling bearings running in an annular race, all substantially as described.

12. An internal combustion engine of the class described having a crank case and crankshaft, a cylinder mounted thereon, the fixed parts of the engine comprising the frame thereof; a combustion chamber within the 25 cylinder and a piston operating therein having pitman connections with the crankshaft; a sleeve valve and casing in working cooperation with the combustion chamber; means for causing suitable rotary movement of the sleeve valve from the crankshaft acting on one side of the valve and adjacent to the periphery thereof; means for preventing rubbing contact and wear of one side of the valve sleeve on said frame caused by the resultant 30 thrust of the valve driving mechanism, said means being adjustable rolling bearings running in an annular race, all substantially as described.

LAURENCE LEIGH MEAD.
